COLLAR OR NECKBAND SUPPORT

James W. Steele, North Kansas City, Mo.

Application October 17, 1938, Serial No. 235,435

5 Claims. (Cl. 223—83)

The present invention relates to garment accessory devices for use in garment-finishing operations for the purpose of maintaining a certain portion of the garment, such as a collar or neckband portion, in correct finished relation, as by supporting and thereby reinforcing the part in proper position during as well as after the finishing operation. More particularly, therefore, the invention relates to supporting devices for use in the finishing of shirts or like garments where suitable supporting or reinforcing means is desirable for preserving the finished condition of the neckband or collar of the shirt in such finishing operations.

Accordingly the primary purpose of my invention is to provide novel collar or neckband supporting devices adapted to be constructed of inexpensive cardboard or similar flexible material, and adapted to effectively hold the meeting end portions of the collar or neckband and also provide an efficient support for bracing the front and side portions of the collar or neckband, and thus preserve the proper shape thereof in the subsequent handling of the garment.

In carrying out these general purposes of the invention, it is also sought to provide a device which may be conveniently manipulated for insertion into operative position within the collar or neckband of the shirt and also adapted for construction to meet the requirements for either a button, or for merely buttonholes at the front meeting ends of the collar portion of the garment. For this purpose the invention comprises means adapted to automatically adapt itself for retaining engagement with the side portions of the collar or neckband and also means for fastening the front end portions thereof by engagement with either buttonholes in said end portions or with a button carried by said end portions, as in the case of the conventional shirt using a permanent button for fastening the ends of the collar.

With the foregoing general objects in view, the invention will now be described by reference to the accompanying drawings illustrating practical forms of embodiment of the improvements for carrying out these various purposes, after which those features and combinations deemed to be both novel and patentable will be particularly set forth and claimed.

In the drawings—

Figure 1 is a perspective view of a neckband type of shirt having the improved supporting device mounted in operative relation;

Figure 2 is an enlarged plan view of the sup-

porting device as stamped from cardboard material and before being applied to the garment;

Figure 3 is a fragmentary perspective view of one end of the supporting device, and illustrating one of the hinged retaining tabs bent into operative position;

Figures 4 and 5 are views similar to Figures 1 and 2, respectively, illustrating an alternative form of construction, adapted for fastening the front ends of the neckband portion of the garment by buttoning over a fastening button at said ends of the neckband;

Figure 6 is a perspective view similar to Figure 1, showing a form of supporting device adapted for buttoning engagement with a button at the front ends of the collar of a collar-attached shirt;

Figure 7 is a fragmentary detail of the tab portion of the device illustrated in Figure 6;

Figure 8 is a perspective view of a shirt illustrating another modified form of construction of the device, of curved outline;

Figure 9 is a vertical sectional view of the neckband and supporting device represented in Figure 8, on a slightly larger scale;

Figure 10 is a perspective view of the form of device shown in Figures 8 and 9;

Figures 11 and 12 are plan views of the improved device made in curved outline and provided respectively with double and single dart-points;

Figure 13 is a plan view showing a straight edge form of support supplied with the hinge tabs for engagement beneath the sides of the collar or neckband opening but omitting the means for directly fastening the front ends of the collar; and

Figure 14 is a fragmentary perspective view of a collar-attached shirt illustrating the strip or band portion of the device inserted between the folds of the collar and its tab portion folded over for buttoning engagement with the stud sometimes used for temporarily fastening the meeting ends of the collar.

Referring now to the drawings in detail, and more particularly to the device as it is illustrated in Figures 1 to 3, the same comprises a strip or band of flexible supporting material adapted to be stamped from a suitable grade of cardboard, to provide the main body strip 14 having the bottom approximately straight edge 15 and the upper edge 16 which may be slightly curved at its mid-portion, as represented in Figures 2 and 3. The length of the strip is sufficient to extend to approximately the opposite rear corners of the

finished collar or neckband 17 of a shirt or like garment 18, when inserted into operative or collar-supporting position as illustrated in Figure 1. In stamping the device, its upper edge 16 is provided with a tab element 19 in position for folding over the front meeting and overlapping ends of the neckband 17, and the outer edge of said tab element is further formed with a dart extension 20 having a laterally projecting point 21, the purpose of which is to project through the buttonholes 22 at the front ends of the collar or neckband 17 (see Figure 9), which are thereby retained in fastened relation by means of said extension threading through said buttonholes 25 and also by the cooperative engagement of the dart point 21 and the shoulder provided by the adjacent edge portion of the tab 19.

When the supporting device is cut with straight bottom edges as shown in Figure 2, there is a tendency of the ends of the strip to spring up in the collar or neckband opening after being inserted in place; and to overcome this I stamp each end of the device with a pivotal or hinge tab element 24 having the hinge or score line 25 and also an extension or tail piece 26 projecting below the edge 15 of the strip or band 14. The construction is such that on engagement of the tail extensions 26 with the shirt inside the collar opening, the tabs are automatically swung from the vertical position shown in Figure 2 to the horizontal position illustrated in Figures 1 and 3, or into just that position necessary for adapting the tabs 24 to be projected laterally outward beneath the neckband 17 into proper retaining engagement therewith, as seen in Figure 1.

The operation and use of the device will be readily understood from the foregoing in the light of the drawings, the operator being simply required to project the dart extension 20 through the matched buttonholes 22 in such fashion as to bring the dart-point 21 into retaining engagement with the inside of the neckband, after which the operator folds the main body portion of the band or strip 14 over to the interior of the collar opening. In this way the dart extension 20 holds the overlapping front ends of the neckband together, and in this relation they are clamped by the tab 19 against the adjacent inner portion of the strip 14. In the folding of the strip 14 over inside the collar opening it is of course bowed sufficiently to be projected into the interior of the collar opening, and as the ends of the device are released at the same time as they are engaged with the body of the shirt inside said collar opening, the tail pieces 26 of the hinge tabs 24 are operated to pivot the tabs about their hinge or score lines 25, thereby resulting in the tabs 24 coming into horizontal position and facilitating their movement outwardly beneath the sides of the collar opening, as shown in Figure 1.

Referring to Figures 4 and 5, these views illustrate a form of construction in which the improved device is provided with a tab 19' for folding over the front ends of a collar neckband, but in place of an extension for threading through the buttonholes 22, this tab 19' is formed with intersecting slits 28 to serve as means for buttoning over the end of the fastening stud 32 ordinarily inserted by the laundry for fastening the ends of the collar or neckband, as is illustrated in Figure 4.

In Figures 6 and 7 the device is illustrated as adapted for use with a collar-attached shirt having the meeting ends of its collar portion 31 pro-

vided with the usual permanently attached fastening button 30. For attaching engagement with this button 30, this form of the support is provided with a relatively narrow extension 20' from the tab element 19"; and instead of the dart shown in Figure 2, said extension 20' is formed with an open-ended slot 27 for forked engagement with the button 30, as clearly represented in Figure 6.

In Figures 8 to 12 of the drawings, the supporting device is illustrated as constructed with a curved type of bracing or supporting strip 14' having the upper and lower curved edges 15', 16', in which form the ends of the supporting device do not have the tendency to spring up out of the collar opening, as referred to in connection with the device as already described; consequently the tabs 24 may be dispensed with in this form of the support.

In the construction illustrated in Figures 8 to 10 the feature of the front tab element 19 is also omitted, but the feature of the dart-extension is retained, this comprising simply the shank portion 20' and dart-point 21' adapted for insertion through the buttonholes 22 of the shirt 18. In 25 assembled relation the strip 14' assumes a position approximately as illustrated in the sectional view shown in Figure 9.

Figures 11 and 12 simply illustrate the same curved support construction as just referred to, but including the feature of the tab element 19 of the form of the device shown in Figures 1 to 6, Figure 12 showing the dart extension as formed with a single dart-point whereas Figure 11 shows the dart extension as provided with double dart-points 21, as may be found desirable by some users of the improved support.

In Figure 13 is shown a straight-edged type of supporting device 14" embodying the hinge-tab features 24-26 at a sufficient number of 40 points to dispense with either the folding front tab or any fastening means at the front ends of the collar or neckband, such as are shown in connection with the previously described forms of the construction. This form or modification is 45 easily inserted into operative position within the collar or neckband opening, and may in some classes of work be found to answer all the requirements without either the front tab feature or the fastening means at the front of the collar, and particularly where such fastening means is 50 already present as shown in Figures 4 to 6. In this form of the device, as well as that illustrated in Figures 6 to 9, it is contemplated that the upper edge of the supporting strip or band will 55 project far enough above the edge of the collar or neckband to provide a guarding or shielding edge for suitably protecting the upper margin of the finished collar or neckband.

In Figure 14 the device is shown as adapted for 60 a slightly different mode of use, the modified construction providing the strip or band 14' with a relatively narrow extension 20" having the intersecting slits 28—similar to the tab 19' of Figures 4 and 5. In the use of this form, the strip or 65 band 14' is inserted between the folds of the collar 31, and then the extension 20" bent over inside the collar opening for engaging the slits 28 with the inner end of the fastening stud 32—as 70 represented by the dotted lines in said Figure 14.

It will therefore be apparent that I have devised a practical and efficient construction for carrying out all the aforesaid objects of the invention, including the provision in a compact and inexpensive supporting device of means for 75

engaging and fastening the front ends of the collar or neckband as well as embracing said ends in overlapping relation by means of a neat and attractive tab element which dresses this most prominent portion of the finished shirt; and also an automatically acting retaining means in the form of hinged tab elements for engaging underneath the sides of the collar or neckband for securely holding the supporting device in its operative position within the collar opening. The device is of such design as to lend itself to very economical and cheap construction by being stamped in quantity production from inexpensive sheet material such as cardboard or the like.

While I have illustrated what I now regard as constituting preferred forms of construction for embodying the proposed features of improvement, it is of course apparent that various minor modifications are possible, varying from the forms illustrated herein, and I therefore desire to be understood as reserving the right to make such modifications or changes as may fairly be deemed to fall within the spirit and scope of the appended claims.

What I claim and desire to secure by Letters Patent is:

1. A collar or neckband supporting device comprising a supporting member embracing the inner or neck-engaging face of the collar opening of a garment, the lower edge of said supporting member being provided with a hinge tab extending to one side of its hinge line for engaging beneath the collar or neckband and having an extension projecting beyond and to the opposite side of said hinge line for actuating the tab into horizontal or operative position.

2. A device of the character described comprising a supporting member embracing the inner or neck-engaging face of the collar or neckband surrounding the collar opening of a garment, the upper edge of said supporting member being formed with a tab folding over the front overlapping ends of the collar or neckband and formed with means for fastening said front ends in said overlapping relation, and the lower edge of said supporting member having one or more hinge tabs for engaging beneath the collar or neckband and formed with extensions projecting out beyond the hinge lines of the tabs for actuating said tabs into horizontal or operative position.

3. A collar supporting device for collar-attached garments comprising a band or strip of flexible material embracing the inner or neck-engaging face of the inner fold of the collar portion of the garment, the upper edge of said strip being formed with an extension folding over the front overlapping ends of the neckband of said collar portion and having means for positively engaging and securing said ends in said overlapping relation, said extension being formed with tab elements connected continuously along their upper edges to said band or strip and projecting laterally over the adjacent front ends of the outer fold of said collar portion for holding the same clamped against said inner fold of said collar portion of the garment.

4. A collar supporting device for collar-attached garments comprising a band or strip of flexible material embracing the inner or neck-engaging face of the inner fold of the collar portion of the garment, the upper edge of said strip being formed with an extension folding over the front overlapping ends of the neckband of said collar portion and terminating in a dart portion projecting through said overlapping ends and having a laterally extending shoulder portion for retaining said ends in their overlapping relation, said extension being also formed with tab elements projecting laterally over the adjacent front ends of the outer fold of said collar portion for holding the same clamped against said inner fold of said garment collar portion.

5. A collar supporting device for collar-attached garments, comprising a band or strip of flexible material embracing the inner neck-engaging face of the inner fold of the collar portion of the garment, the upper edge of said band or strip being formed with an extension folding over the front overlapping ends of the neckband of said collar portion and having means projecting through said ends for securing the same in said overlapping relation, said extension being also formed with integral tab elements connected throughout their length with said upper edge of the band or strip and projecting laterally over the adjacent front ends of the outer fold of said collar portion and thereby clamping the same firmly against the inner fold of said garment collar portion.

JAMES W. STEELE. 50
